UNITED STATES PATENT OFFICE.

JOHN J. KUHN, OF ELIZABETH, NEW JERSEY, AND WALTER L. BETTS, OF BROOKLYN, NEW YORK, ASSIGNORS TO WESTERN ELECTRIC COMPANY, INCORPORATED, OF NEW YORK, N. Y., A CORPORATION OF NEW YORK.

SWITCHING DEVICE.

Application filed December 24, 1925. Serial No. 77,664.

This invention relates to switching devices and more specifically to a type of switching device particularly well adapted for use for controlling the volume in a 5 radio amplifier circuit and the like.

The object of this invention is to provide a switching device and circuit arrangement whereby the volume of input energy in a radio amplifier circuit may be controlled in 10 a simple and positive manner.

A feature of the invention is the provision of a switching device having a set of connected resistances, a cam being provided on the shaft which when the brush 15 leaves the last resistance element shifts a set of contacts to connect an additional portion of the secondary winding of the input coil to the grid circuit to change the gain, the said resistances being connected in 20 multiple to a second set of terminals over which the brush sweeps in the other half of its movement.

Other features and advantages will appear from the following description and 25 by the claims appended thereto, reference being had to the accompanying drawing in which the reference letter CA indicates an amplifier circuit arrangement and SD a switching device constructed according to 30 the features of this invention.

In its preferred form the switch comprises a knob 10 adapted to be manually operated for moving a switch wiper 11 in 35 contacting relation with sets of contact members such as 12, 13, 14, and 12', 13', 14' etc., which are preferably mounted in an arcuated row on a suitable panel not shown. Contacts 12, 13 and 14 are connected to 40 tapped off portions of potentiometer P, each contact 13, 14, etc. being multiplied in a consecutive order to contacts 13', 14', etc.

The knob 10 and wiper 11 are securely mounted on a shaft 15 which carries a cam 16, disposed in operable relation with the 45 free end portion of a resilient contact operating member 17. The position of cam 16, with respect to wiper 11 and the contact members 12, 13, 14 and 12', 13', 14' etc., is such that when the wiper 11 is moved from 50 contact 12' in a counter clock-wise direction, the cam 16 engages the contact operating member 17 for breaking the contact between springs 18 and 20 and simultaneously closing the contact between springs 21 and 20,

the spring 20 being brought in contacting 55 relation with the contact spring 21, through the medium of its own tension.

These contact springs form parts of the amplifier circuit adapted for operating a telephone receiver TR which may be of the 60 loud speaker sort used in public address or similar system. As shown in the drawing this amplifier circuit may comprise a vacuum tube repeater 25 constituting the first stage of amplification and the vacuum tube 65 26, the second stage of amplification. The filament current for the tubes 25 and 26 is supplied by batteries 32 and 33 respectively. The tubes 25 and 26 are each illustrated as 70 three element tube electron discharge device. Each comprises an anode, a cathode, and a control electrode. The grid or control electrode of tube 25 is connected to the incoming line 28 by a transformer 27 having a primary and secondary winding. The 75 grid of tube 26 is connected to contacts 12, 13, 14, etc. and resistances 35, 36, etc. of the switching device through wiper 11, thus providing means for controlling the voltage impressed on the grid of tube 26 from 80 the plate of tube 25. The leads 29 tapped off from a portion of the secondary of transformer 27 and the lead 31 from the whole of the secondary are connected to contacts 85 18 and 21 respectively. In the position of the springs shown in the drawing the portion 30 of the transformer secondary winding is associated with the switching device and the receiver TR through an obvious circuit. Upon the operation of contact spring 90 18 and the simultaneous closure of contact springs 21 and 20 when the wiper 11 engages the contact 13', the circuit which includes lead 29 connected in the middle portion of the secondary winding of the transformer is opened and the other half portion of the secondary coil added in the new operating circuit which now includes lead 31. Through the closure of contact springs 95 20 and 21, the added portion of the transformer secondary coil together with resistances 35 and 36, etc., multiplied to contacts 13', 14', etc., permit the control of the volume input in 11 additional steps by using the resistances, previously used in a similar 100 consecutive order.

With this switching arrangement it is to be noted that the number of controlling

steps to which this arrangement is capable is limited only by the number of tapped off portions taken from the potentiometer or the number tapped off portions taken from the secondary winding of the transformer.

What is claimed is:

1. In an intelligence signaling system, the combination with a radio amplifier circuit, 10 a switching device comprising sets of contacts, a wiper, a shaft for moving said wiper in contacting relation with each of said contacts, resistances connected to one of said sets and multiplied to the contacts of the other set, sets of normally open and closed contact springs, a transformer having portions of its output winding connected to said contact springs, and means operated by the switch shaft for actuating said springs for 20 associating portions of the transformer with said resistances for controlling the volume output in the amplifier circuit.

2. In an intelligence signaling system, a switching device, sets of multiplied contacts 25 arranged in a contiguous row, a potentiometer having tapped off portions connected to said contact sets and in consecutive order relative to each other, a wiper adapted to be moved in contacting relation with the contacts of each of said sets, a set of contact springs, a transformer having tapped off portions connected to said springs, an amplifier tube, and a camming member for actuating said springs for associating the 35 tapped off portions of the transformer through said tube with the tapped off portions of the potentiometer, the potentiometer being effective to control the volume output

of said transformer portions singly or collectively upon the movement of said switch- 40 ing device.

3. In an intelligence signaling system the combination with a transformer, of a potentiometer, a switching device, including a movable wiper, sets of multiplied contacts 45 connecting portions of said potentiometer to said wiper, an amplifier tube, a set of contact springs and a cam operable through the movement of said wiper for actuating said springs whereby a movement of the wiper 50 in a consecutive order on the multiplied contacts is effective to associate said potentiometer through said tube with different sections of said transformer.

4. In an intelligence signaling system, the 55 combination with an amplifier circuit, a switching device comprising sets of contacts, a potentiometer having tapped off portions connected to one set, and multiplied to the other set, a wiper movable in contacting relation with each of said contacts, a transformer having portions of its output winding normally ineffective with respect to said circuit, means for moving said wiper in contacting relation with the contact of the first 60 set for controlling the volume output portion of the connected portion of said transformer, and means operable upon the movement of the wiper toward the first contact of the second set to render the entire transformer 65 70 winding effective with respect to said circuit.

In witness whereof, we hereunto subscribe our names this 17th day of December, A. D. 1925.

JOHN J. KUHN.
WALTER L. BETTS.
